(57) **CLAIM**

The ornamental design for “electrical transformers,” as
shown and described.

DESCRIPTION

FIG. 1 is a front view of a first embodiment of an electrical
transformer;

FIG. 2 is a top view of said first embodiment of an electrical
transformer;

FIG. 3 is a side view of said first embodiment of an electrical
transformer;

FIG. 4 is a rear perspective view of said first embodiment of
an electrical transformer;

FIG. 5 is a front perspective view of said first embodiment
of an electrical transformer;

FIG. 6 is a front view of a second embodiment of an
electrical transformer;

FIG. 7 is a top view of said second embodiment of an
electrical transformer;

FIG. 8 is a side view of said second embodiment of an
electrical transformer;

FIG. 9 is a rear perspective view of said second embodiment
of an electrical transformer;

FIG. 10 is a front perspective view of said second embodiment
of an electrical transformer;

FIG. 11 is a front view of a third embodiment of an electrical
transformer;

FIG. 12 is a top view of said third embodiment of an
electrical transformer;

FIG. 13 is a side view of said third embodiment of an
electrical transformer;

FIG. 14 is a rear perspective view of said third embodiment
of an electrical transformer;

FIG. 15 is a front perspective view of said third embodiment of an electrical transformer;
FIG. 16 is a front view of a fourth embodiment of an electrical transformer;
FIG. 17 is a top view of said fourth embodiment of an electrical transformer;
FIG. 18 is a side view of said fourth embodiment of an electrical transformer;
FIG. 19 is a rear perspective view of said fourth embodiment of an electrical transformer;
FIG. 20 is a front perspective view of said fourth embodiment of an electrical transformer;
FIG. 21 is a front view of a fifth embodiment of an electrical transformer;
FIG. 22 is a top view of said fifth embodiment of an electrical transformer;
FIG. 23 is a side view of said fifth embodiment of an electrical transformer;
FIG. 24 is a rear perspective view of said fifth embodiment of an electrical transformer;
FIG. 25 is a front perspective view of said fifth embodiment of an electrical transformer;

FIG. 26 is a front view of a sixth embodiment of an electrical transformer;
FIG. 27 is a top view of said sixth embodiment of an electrical transformer;
FIG. 28 is a side view of said sixth embodiment of an electrical transformer;
FIG. 29 is a rear perspective view of said sixth embodiment of an electrical transformer;
FIG. 30 is a front perspective view of said sixth embodiment of an electrical transformer;
FIG. 31 is a front view of a seventh embodiment of an electrical transformer;
FIG. 32 is a top view of said seventh embodiment of an electrical transformer;
FIG. 33 is a side view of said seventh embodiment of an electrical transformer;
FIG. 34 is a rear perspective view of said seventh embodiment of an electrical transformer; and,
FIG. 35 is a front perspective view of said seventh embodiment of an electrical transformer.
